UNITED STATES PATENT OFFICE.

GEORGE B. FROST, OF DES MOINES, IOWA.

STOCK-FEEDING DEVICE.

1,368,553.

Specification of Letters Patent. Patented Feb. 15, 1921.

Application filed May 13, 1919. Serial No. 296,834.

To all whom it may concern:

Be it known that I, GEORGE B. FROST, a citizen of the United States, and resident of Des Moines, in the county of Polk and State 5 of Iowa, have invented a certain new and useful Stock-Feeding Device, of which the following is a specification.

The object of my invention is to provide a stock feeding device of simple, durable and 10 inexpensive construction.

More particularly it is my object to provide a stock feeding device having adjustable means for regulating the flow of feed from the hopper into the feeding troughs.

15 A further object of my stock feeding device is to provide means for having only a portion of the total amount of feed exposed at any one time.

Still a further object is to provide a stock 20 feeding device having a hopper with an adjustable closure device for regulating the discharge of feed therefrom, and a removable trough for receiving feed from the hopper, the closure device having a movable 25 member designed to project downwardly into said troughs and to be movable to a position for permitting said troughs to be removed.

With these and other objects in view, my 30 invention consists in the construction, arrangement and combination of the various parts of the device, whereby the objects contemplated are attained, as hereinafter more fully set forth, pointed out in my claims, 35 and illustrated in the accompanying drawings, in which:

Figure 1 shows a side elevation of a stock feeding device embodying my invention.

Fig. 2 shows a transverse sectional view, 40 taken on the line 2—2 of Fig. 1, and

Fig. 3 shows a sectional view, taken on the line 3—3 of Fig. 2.

In the accompanying drawings I have used the reference numerals 10 and 11 to indicate the end members of the stock feeding device. A movable top member 13 adapted to be opened for filling the device is provided. In the form shown the top or cover member consists of a fixed member and a hinged member. The base 12 is securely fastened to the end members 10 and 11. Between the ends 10 and 11 is a hopper having converging longitudinal sides 14 and 15, from which wall members 16 and 17 extend 50 downwardly.

Fixed in the hopper is a divider ridge 18,

which causes the feed to be distributed on each side thereof. The lower edges 19 of the ridge 18 are so spaced above the troughs 20 as to always insure the flow of feed into the 60 troughs, and may be vertical to stiffen the ridge when the latter is made of metal.

Each trough 20 has end members 21, to which is fastened a longitudinal bar 22, and has a series of transverse bars 23 extending 65 from the bar 22 to the front of the trough for dividing the trough into feeding compartments.

The walls 16 and 17 are provided with 70 guides 24, in which are slidably mounted closure devices 25, having slots 26 therein. Screw bolts 27 are mounted in the walls 16 and 17, and extend through the slots 26 of the closure devices 25, and have on their outer ends thumb nuts 27a. 75

At the lower end of each closure device 25 is a hinged member which normally extends outwardly at 28 and downwardly at 29. The portions 29 extend into the troughs 20, and limit the amount of feed which will pass 80 from the hopper into the troughs by retarding the flow of grain and preventing over-flowing the troughs. The outward swinging movement of the member 29 which might be caused by the pressure of the feed in the 85 hopper, is limited by the longitudinal bar 22 of the trough 20. By loosening the thumb nuts 27a and raising or lowering the closure device 25, the opening at 30 can be varied in size, so that the flow of feed passing into the 90 troughs can either be increased or diminished, as desired.

The troughs 20 are removable and can easily be cleaned when removed by merely filling the troughs with water and then 95 emptying them. The troughs when in the feeding device are prevented from any inward movement by the stops 31, and from any outward movement by the angle bars 32, or other suitable means. An arm 33 pivoted 100 at 34, prevents any upward movement caused by the animals feeding from said troughs.

My device may be provided with a swinging door 35 hinged at its upper end by a 105 hinged member 36. The door 35 normally hangs in its closed position. The animals in order to obtain the feed, push the door inwardly. As the feed becomes eaten farther into the trough the animal by rooting pushes 110 the door 35 until it strikes the hinged agitator 29, thereby loosening the feed in the

passage way and causing it to flow into the trough. This door is shown on one side of Fig. 2 and is in section. It will be seen that by the use of this door chickens and the like will be kept from consuming the feed.

In Fig. 1 in dotted lines is a partition member 37 which provides a method for feeding different kinds of feed at the same time in the feeder.

10 To remove the trough 20 the closure device 25 is lowered for closing the opening 30 for stopping the flow of grain. The outer edge of the trough 20 is then lifted upwardly until its lower end clears the angle bar 32. The trough is then pulled out. The member 29 being pivotally mounted on the closure device 25 and extending into the trough 20, swings outwardly enough to allow the trough 20 to be readily removed.

20 In the practical operation of my device, feed is deposited in the hopper of the feeding device. The opening 30 is then adjusted so as to limit the flow of feed from the hopper into the troughs 20, by means of adjusting the closure device 25, which is held in any position by the thumb screws 27 and thumb nuts 27^a. The feed is thus limited as to the rate of flow, by the size of the opening 30. Feed passing through the 30 opening 30 will pass downwardly until it is received in the troughs 20, the inner edges of which are directly below the outlet of the hopper. The members 29 limit the amount of feed that will thus be deposited in the 35 troughs 20.

The feed passing from the hopper into the troughs 20 will fill the troughs substantially as indicated by the dotted lines 40 in Fig. 2. As soon as the feed is deposited in 40 the troughs 20, substantially as indicated by the dotted lines 40 in said figure, it causes the outlets of the hopper to become sealed, which stops the flow of feed. As the feed in the troughs 20 is eaten by the stock, the 45 feed will continue to flow from the hopper into the troughs and always maintain a supply of feed in the trough substantially as indicated by the said dotted lines.

If from any cause, the feed becomes 50 clogged in the opening 30 and the feed in the troughs 20 is entirely eaten out, the stock, by rooting against the lower end of the hinged member 29, will cause it to be agitated, thereby loosening the clogged feed in 55 the opening 30 until it is free to pass into the troughs 20.

It will readily be seen that with my device, the troughs being removable by quick and easy process enables them to be readily 60 cleaned and placed back in the feeding device without any great amount of work and without any adjustment whatever of any of the parts. The removing and cleaning of the troughs, which is readily accomplished, insures a sanitary device for stock feeding.

One of the advantages of my device is that when the troughs are to be removed the closure devices are lowered until the outlets from the hopper are entirely closed. This prevents a loss of any of the feed 70 while the troughs are removed.

It will also be seen that with my construction if it is desired to feed from only one side of the feeding device, one closure member may be entirely closed, allowing feed to 75 flow from only one of the outlets of the hopper.

Another advantage of my stock feeding device is that a large supply of feed may be placed in the hopper and yet the amount of 80 feed exposed to the weather is very limited.

Another advantage is that when the hopper outlets become clogged, the agitators formed by the members 29 are operated by the stock rooting against them. This agitation causes the feed to be loosened until it is allowed to pass freely through the opening from the hopper into the feeding troughs.

By making the hopper in the form shown 90 the troughs are given considerable protection by overhanging walls and yet said walls are far enough above the troughs to permit access to the troughs by large hogs.

It will be understood that some changes 95 may be made in the construction and arrangement of the various parts of my stock feeding device without departing from the essential features and purposes thereof, and it is my intention to cover by the claims of 100 my patent any modified forms of structure or use of mechanical equivalents which may be reasonably included within the scope of said claims.

I claim as my invention:

1. In a stock feeding device, a frame, spaced troughs, a hopper on said frame above said troughs, having at its upper portion downwardly converging side members, having at their lower ends downwardly extending side wall members, inclined bottom members in said hopper, said wall members each having thereon an adjustable member arranged to coat with one of the inclined bottom members for controlling the flow of 115 food from the hopper, and being provided with a hinged portion, projecting outwardly and downwardly into one of said troughs, each trough having means between its side edges for limiting the swinging movement 120 of said hinged portion.

2. In a stock feeding device, a hopper having an inclined upper wall, and a downwardly extending wall at the lower end thereof, an inclined bottom member in said hopper, a closure device adjustably mounted on said downwardly extending wall member, and adapted to coat with said inclined bottom member for controlling the flow of feed 125 from said hopper, a trough arranged to re- 130

- ceive feed flowing from said hopper, a swinging closure member hinged adjacent to the upper end of said hopper, and hanging downwardly, and tending to normally stand above 5 the outer edge of the trough so as to form a closure device for protecting the contents of the trough, a swinging member on the lower edge of said adjustable closure device, extending outwardly and downwardly away 10 therefrom into the trough, and adapted to be struck by said hanging member when the hanging member is moved inwardly to a proper point, and thereupon to serve as a feed agitator, and means for limiting the 15 outward swinging movement of said agitator.
3. In a stock feeding device, a frame, a hopper on said frame, having an outlet, a removable trough, having a portion projected beneath said outlet, and an adjustable closure device adapted in various positions to control the size of said outlet, and in one 20 position to close said outlet, a downwardly hanging device pivotally supported on said
- closure device, and arranged to project into 25 the trough, the parts being so arranged that the trough may be moved away from its position beneath the outlet and said downwardly hanging device may be swung to position for permitting such movement. 30
4. In a stock feeding device, a hopper having an outlet, a removable trough arranged with a portion projecting beneath said outlet, an adjustable closure device for 35 said outlet, a hinged member on said closure device, projecting into said trough, means for preventing the horizontal movement of said trough, a swinging member adapted normally to prevent the raising of the 40 trough, the parts being so arranged that when said swinging member is moved away from its normal position, the trough may be lifted and taken away from its position beneath said outlet, and the hanging member will move pivotally to permit such movement of the trough. 45

Des Moines, Iowa, April 5, 1919.

GEORGE B. FROST.
